UNITED STATES PATENT OFFICE.

ARTHUR JAMES BILLOWS, OF LONDON, ENGLAND.

MACHINE FOR FILLING AND SEALING BOTTLES.

Application filed September 8, 1922. Serial No. 586,939.

To all whom it may concern:

Be it known that I, ARTHUR JAMES BILLOWS, a subject of the King of Great Britain and Ireland, and a resident of London, county of London, England, have invented a certain new and useful Improvement in Machines for Filling and Sealing Bottles, of which the following is a specification.

My invention, which relates to a machine for filling and sealing bottles, is characterized in that, after filling and snifting, the sealing is effected by means of a metal disc cap, or by screw stopper, or by an internal stopper, according to the type of bottle used, all being done while under pressure and by one and the same machine, herein-after termed rack, either operated by rotary movement or stationary.

In order that my said invention may be the more readily understood, reference is to be had to the following description and accompanying sheets of drawings illustrative of the rack as applied to sealing by means of metal disc caps, and wherein:

Figure 1 is a front view, partly in elevation and partly in section, of the rack in position ready to receive a bottle.

Figure 2 is a similar view, but showing a bottle in position ready for filling and sealing.

Figure 3 is a side view, partly in section and partly in elevation, of the rack shown in said Figure 2.

Figure 4 is an underside plan view taken on line 4—4 of Figure 1.

Figure 5 is a side view of the catch plate shown in Figure 4.

Figure 6 is a view, partly in section and partly in elevation, and drawn to an enlarged scale, of the slidable chuck herein-after referred to.

Figure 7 is a top plan view thereof.

Figure 8 is a top plan view, partly in section and partly in elevation, and taken on line 8—8 of Figure 1.

Figure 9 is a plan view of the striking bush hereinafter referred to.

Fig. 10 is a side elevation of the striking bush shown in Fig. 9.

Like numerals of reference indicate corresponding parts in the several figures.

In carrying out the invention, and referring to the drawings, the head 3 of the rack is provided with an inlet 4 which communi-

cates with a suitable rotatable connection 5 of a carbonating machine, and said head carries at its upper end a rubber ring 6, into which the neck 7 of the bottle 8 to be filled and sealed is inserted, the bottom of said bottle 8 being engaged by a bottle plate 9 carrier by a screw-threaded rod 10 rotatable in the upper bridge piece 11 of the rack, said screw-threaded rod 10 being provided with a hand wheel 12, and said bridge piece 11 with a set screw 13 to lock the screwed rod 10 when the bottle plate 9 is in adjusted position.

In the head 3 of the rack there is arranged a vertically slidable chuck 14, the same consisting of a cylindrical member provided externally with vertical grooves 15 in which are fitted fingers 16, each provided at their upper end with an inturned projection 17, said fingers 16 being resiliently held in position in said vertical grooves 15 by means of a rubber band 18, said cylindrical member 14 being, as shown in the drawings, formed in one piece. The band 18 possesses sufficient tensile

strength to draw the projections 17 of the finger 16 into engagement with the cap and form a groove therein about the beads of the bottle when relative turning movement takes place between the bottle, the cap and the fingers. This operation, is a common expedient. It will be observed that the upper surfaces of the projections 17 are inwardly and downwardly inclined and consequently the mouth of the bottle may readily enter between the fingers. After the groove is formed and the fingers are moved away from the bottle the projections 17 will slip transversely across those edge portions of the cap which have been crimped or grooved into engagement with the neck of the bottle as stated.

The chuck 14 is carried at the upper end of a screw-threaded rod 19 by means of a bush 20 screwed into the lower end of said chuck 14 and a headed pin 21 rotatable in said bush 20 and fixedly carried by the upper end 22 of said screw-threaded rod 19, said rod 19, which is provided with an operating hand wheel 23 with a striker or resetting cam 24 thereon, screwing in the movable bridge piece 25 of the rack, which lower bridge piece 25, as well as the head 3, is carried by the lower ends of vertically disposed

guide rods 26 slidably mounted in the top bridge piece 11.

The spindle 27 of the hand wheel 23 is rotatably mounted in the bottom bridge piece 28 of the rack, said bottom bridge piece 28 being fixedly connected to the top bridge piece 11 by means of vertically disposed rods 29, and through said bottom bridge piece 28 are adapted to slide stop pins 30 carried by the movable bridge piece 25, said stop pins 30 at their lower ends being provided each with a roller 31 adapted to engage the spring-controlled striking or locking plate 32 which is rotatably mounted on the bottom bridge piece 28 aforesaid.

34 is the snift passage leading to atmosphere from the filling chamber 35 in the rack head 3, said snift 34 being closed by valve 36 carried by a spring-controlled lever 37 pivotally mounted on the rack head 3, said lever carrying a roller 38 adapted to engage a cam 39 on a suitable part of the carbonating machine.

In use, the bottle plate 9 is adjusted to suit the length of bottle, and then locked in position. A metal disc cap 40 is then pressed into the cap affixing chuck 14 which is of the type ordinarily used to place metal caps on bottles, the said cap being retained under the inturned fingers 17 thereof by means of a spring-controlled plunger 41a slidably mounted in said chuck 14, chuck 14 being in the position shown in Figure 1. The neck 7 of the bottle 8 is then inserted into the rubber ring 6, the bottom of bottle resting against the bottle plate 9. Hand wheel 23 is then turned in a counter-clockwise direction and, through the movement of the screw 19, pushes the head 3 and movable bridge piece 25 upwards against the action of the springs 41 anchored to the bridge pieces 25 and 28, till the arms 42 of said head 3 contact with the adjustable stops 43 on the rods 29 which connect the bridge pieces 11 and 28 together. As this takes place, the rollers 31 of the stop pins 30 are raised clear of the hook portions 44 of the striking plate 32, which plate 32 under the action of its spring 45 flies back till brought to rest by a stop 46, the rollers 31 then coming to rest on the upper faces of the hook portions 44 of said striking plate 32, as in Figure 2, the upward movement of the head 3 and bridge piece 25 bringing the rubber ring into intimate and liquid-tight contact with the bottle neck.

Carbonated liquid is now admitted by way of passage 4 into the filling chamber 35 in the head 3, and the rack is rotated by means of handle 49 carried by the upper bridge piece 11 of the rack, shifting taking place each time the roller 38 of the snift valve 36 passes over the cam surface 39 of the carbonating machine.

25. Bottle being filled, and rack brought to

the vertical position, the hand wheel 23 is further rotated clockwise, causing the screw 19 to travel upwards in the movable bridge piece 25, spindle 27 of said screw 19 sliding in the bottom bridge piece 28, pushing the chuck 14 and the metal disc cap 40 therein into contact with the mouth of the bottle 8, closing said disc cap on to the mouth of said bottle by crimping it thereon in the usual manner. Almost at the same time as this takes place, projections or shoulders 47 on the striker 24 carried by the operating hand wheel 23, engage corresponding projections 48 on the striking or locking plate 32 on the bottom bridge piece 28, resetting or pushing said striking plate 32 back, against the action of its spring 45, till the hook portions 44 of the striking plate are moved away from below the rollers 31 of the stop pins 30. Immediately this takes place, the head 3, movable bridge piece 25, the chuck 14 and screw 19 and hand wheel 23 and with it the striker 24, all move downwards under the action of the springs 41 anchored to the bottom bridge piece 28, withdrawing chuck 14 from bottle mouth, leaving the same closed by the metal disc cap, whereupon on the liquid supply being cut off, the bottle can be removed, and the various operations repeated for each succeeding bottle.

Further, although the invention has only been described and shown with the use of a rotatable rack, yet a stationary rack may be equally well employed, and in this case, the shifting will be effected in any convenient and suitable manner.

I claim:—

1. A machine for filling and sealing bottles comprising top and bottom bridge pieces connected by vertical rods, a head 105 slidably mounted on the rods, a sealing gasket in said head, a chuck also in the head below the sealing gasket, guide rods carried by the head and slidably engaging the top bridge piece, retracting springs connecting the head with the bottom bridge piece, stop pins carried by the head, a striker plate for automatically locking said stop pins in an elevated position, a spindle having a screw part engaging in a portion of said head and adapted to operate the chuck, and a resetting cam carried by the spindle and adapted to release the striking plate from locking engagement with said stop pins after the bottle has been sealed. 110

2. A machine for filling and sealing bottles while under pressure including a rigid main frame, an adjustable bottle abutment at one end thereof, a vertically movable filling head slidably engaging the sides of the main frame, a compressible rubber ring in said head, springs for maintaining said head in a lowered position, means for advancing the head to cause the rubber ring to grip the neck of the bottle, a capping 125

chuck in said head, a spindle for operating said chuck, means for locking said head while the bottle is being filled, and means for releasing said head after the bottle has 5 been capped.

3. A machine of the class described including a frame, an adjustable bottle abutment at one end of the frame, a head having arms slideable in the frame, stops carried by 10 the frame and adapted to be engaged by said arms, a collapsible rubber ring mounted in said head, springs for retracting said head away from said stops, a spindle having a screw portion for elevating said head against the tension of the 15 spring and the initial movement of said head causing the rubber ring to compress and engage the neck of a bottle, a chuck in said head operated by the further movement of said spindle thereby to cap the 20 bottle, means for locking the head in its filling and capping position, and means associated with the spindle and controlled

thereby for releasing said means for locking the head. 25

4. In a machine of the class described, a frame including side rods and top and bottom bridge pieces, a filling head mounted for vertical movements between the side rods, springs connecting said head to the 30 bottom bridge piece, a spindle having a screw portion for advancing the head in opposition to the springs, a spring controlled striking plate associated with the bottom bridge piece, vertical stop pins carried 35 by the lower portion of the head, rollers carried by the ends of said pins and adapted to engage the said striking plate, a member carried by the spindle and adapted to engage with the striking plate to move the 40 same out of the way of the rollers on the stop pins to permit the springs to return the head to its normal position.

In testimony whereof I have affixed my signature hereto this 26th day of July, 1922.

ARTHUR JAMES BILLIWS.
